[57] CLAIM

The ornamental design for a power converter module, as shown and described.

DESCRIPTION

FIG. 1 is a perspective view of a power converter module showing a first embodiment of our new design;

FIG. 2 is a front elevation view thereof; the rear elevation view thereof being identical to said front elevation view;

FIG. 3 is a top plan view thereof; the bottom plan view

thereof being flat, planar, and containing no ornamentation;

FIG. 4 is a right side elevation view thereof; the left side elevation view thereof being a mirror image of said right side elevation view;

FIG. 5 is a top plan view of a power converter module showing a second embodiment of our new design; the bottom plan view thereof being flat, planar, and containing no ornamentation;

FIG. 6 is a right side elevation view of said second embodiment; the left side elevation view thereof being a mirror image of said right side elevation view;

The front elevation view of said second embodiment being identical to said front elevation view of said first embodiment shown in FIG. 2; and the rear elevation view thereof being identical to said front elevation view of said first embodiment shown in FIG. 2;

FIG. 7 is a front elevation view of a power converter module showing a third embodiment of our new design; the rear elevation view thereof being identical to said front elevation view;

FIG. 8 is a top plan view of said third embodiment; the bottom plan view thereof being flat, planar, and containing no ornamentation;

FIG. 9 is a right side elevation view of said third embodiment; the left side elevation view thereof being a mirror image of said right side elevation view;

FIG. 10 is a top plan view of a power converter module showing a fourth embodiment of our new design; the bottom plan view thereof being flat, planar, and containing no ornamentation;

FIG. 11 is a right side elevation view of said fourth embodiment; the left side elevation view thereof being a mirror image of said right side elevation view; and, The front elevation view of said fourth embodiment being identical to said front elevation view of said third embodiment shown in FIG. 7; and the rear elevation view thereof being identical to said front elevation view of said third embodiment shown in FIG. 7.
